UNITED STATES PATENT OFFICE.

CONRAD EHRET, OF OKLAHOMA CITY, OKLAHOMA.

CLOSURE FOR THIEF HOLES FOR TANKS AND OTHER RECEPTACLES.

Application filed August 7, 1926. Serial No. 127,786.

My invention relates to improvements in closures for thief holes for tanks and other receptacles.

The object of my invention is to produce a device of the character described, which will be new, novel and of practical utility; simple, strong, durable, easily attached and detached, not liable to get out of order, easily and cheaply constructed and manufactured, quickly and securely closing the aperture or opening of a thief hole of a tank or other receptacle; which will be more efficient in securely holding the rubber ring so as to at all times fit the rim or top of the hole, and yet so that the same will not become adhered to the rim or other parts and be drawn thereby out of its holding; which will be efficient in not requiring the use of bolts, nuts, taps, wrenches, or other appliances in fastening or unfastening the same; which will be efficient in saving or preventing the escape of gas, or liquid, caused by rusting, decaying, or the wearing out of the parts of metal around the hole, or the bolts, or the like; and which will be more efficient in opening and closing at all times.

The invention, new and novel features, and other objects and advantages will be set forth in the ensuing description, specification, claim and accompanying one sheet drawing, of which,

Figure 1 is a plan view of the thief hole cover; Fig. 2 is a side view showing the position of the lid open in dotted-in portions; Fig. 3 is a perspective view of an arm of the lid showing an outstanding lug; Fig. 4 is a perspective view of the receiver for the arm a recess for receiving the outstanding lug of said arm; Fig. 5 is a section view of a portion of the lid showing the means of holding gasket in place and the shape of the rubber.

Like characters of reference designate like parts in all the figures.

The manner of accomplishing the purposes for which my invention is intended is as follows:

The device consists of a hole cut in a tank or other receptacle, an upwardly extending rim 1, 2, thereover, securely bolted through holes 52 in a flared shoulder 3 therein, which are fastened by holding means (not shown) to the tank or other receptacle. Attached to shoulder 3 and rim 1, 2, are two outwardly and upwardly extending members or lugs 22, each partially perforated 25 therethrough,

and each partial perforation having an outwardly and upwardly cut channel 24 therefrom to its outward and upward surface under its top portion 23. Between each of said top portions 23 of said lugs 22 and the rim 2 is a rounded recessed portion 26 to increase the facility of opening said lid 9, from said rim 1, 2. On the outer surface of the walls of said rim 1, 2, are two C-shaped flat lugs 5 oppositely each other and at right angles to said lugs 22. In the centers of said C-shaped lugs 5 is a hole (not numbered) extending only through said lugs to the outer surfaces of said rim 1, 2; from said hole is an upwardly pointing channel or cut between 6 and 7 pointing towards the upper portion of said lugs 22 and extending only to the outer surface of said rim 1, 2. The closure 9 is cymbal-shaped, having an outer raised center 9^a and an inner thimble-shaped central depression 50 therein. It also has a flat outer shoulder 10 at its periphery perforated so as to receive countersunk screw-bolts 28 held by nuts 29. Said bolts and nuts securely hold a metallic ring 27 to said shoulder 10. Said shoulder has its outer and under periphery cut out on a straight line 30 between 33 and 34 and downwardly therefrom to 35, horizontally and parallel with said first described line to 36 then straight downwardly to 37. A solid rubber ring 38, its lower surface 39 adapted to be seated on the upper edge 4 of rim 1, 2, is of the same shape as the inner cut-out portion of said shoulder 10. Its lower surface 39 is adapted to extend below line 37 of said cut-out portion of said shoulder 10. The outer surface of said rubber ring 38 is tapered upwardly and outwardly on an angle of approximately 60° between 31 and 32 adapted to fit an oppositely tapering and similarly angled inner surface 44 of said metallic ring 27. This ring 38 may also be made of other suitable material, besides rubber. The upper surface on line 30 and the outer surface 42 and the lower surface 43 of said ring 27 are at right angles with each other; its inner surface 44 is tapered at an angle of approximately 60° between 32 and 41. Said metallic ring 27 is perforated (not numbered) in line with the perforations in shoulder 10 to admit countersunk screw-bolts 28 fastened by nuts 29. This presses inner edge 44 thereof snugly against outer edge 40 of said

100
105
110

rubber ring 38 and presses tongue 45 into groove between 34 and 35, thereby preventing the pulling out of said rubber ring 38 from its seat by reason of becoming adhered to upper edge 4 of rim 1, 2.

The closure is opened by unscrewing the hand hold 48 and loosening stem screw 11 through similarly threaded perforation 49 in the bail head 51, of bail member 46, 47, 10 and out of inverted thimble-shaped recess 50; bail 46, 47 can then be laid down over the lid or top oppositely to said foot-hold 13; the foot-hold 13 on the outer end of arm 12 can be pressed downwardly raising the lid or top 9 upwardly and outwardly until it assumes the position shown by the dotted-in portions and until outer edge 14 and lower end 15 rest in the position shown in said dotted-in portion and said 15 rests partially against the rim 2. If it is desired to remove the lid 9 from its partial perforations 25 in lugs 22 this may be done by raising the lid 9 having arms 17, 20, until lugs 18, 21 having faces 19 on lugs 18 opposite face 16 of opening 24 in partial perforations 25, said lug 18 can then be withdrawn through groove 24 and the lid 9 with its various parts removed from its regular seat. The replacing is by an opposite process to that just described. After the removal of the lid 9 as described if it is then desired to remove the bail, member 46, 47, this may be done in a similar manner to that just described for removing the lid 9, by changing the position of said bail member from the position in which it has been described to the side where said lugs 22 are located, until the straight D-shaped side 8 is in line with surface 7 of the groove between 6 and 7, at which time the D-shaped end of said bail member may be removed from the C-shaped lug and the bail removed. Said shoulder 10 has an outstanding lug 53 to limit the bail member 46, 47, in its movement.

The parts described in the above specification and illustrated by the drawing which are covered by patent issued this applicant under date of April 27, 1926, and numbered 1,582,209, under the claims therein allowed, are not claimed as new herein; such other parts of this application and drawing as are not covered by the said issued patent and the claims thereof are claimed herein. The parts which are particularly claimed

herein as new are the shape of the rubber ring 55 and its holding members and the manner of keeping it in its seat, and the manner of hinging the lid or closure, and the removing of it from its settings.

By certain minor changes said invention 60 may be adapted for use in connection with man-holes, and other holes for tanks and other receptacles.

From the description and the accompanying one sheet drawing and the specification, 65 the advantages of construction, manufacture, and application of the invention will be apparent to those skilled in the art to which my invention pertains. I have entered into a detailed description of the construction 70 and relative arrangement of parts embraced in the present and preferred embodiment of my invention in order to impart a full, clear and exact understanding of the said embodiment. I do not desire, however, to be understood as confining myself to the specific construction and relative arrangement of the parts, inasmuch as in the future practice of the invention various changes and modifications may be made as fall within the scope 75 of my invention as defined in my appended claim.

Having thus described the invention, what is claimed and desired to be secured by Letters Patent, is:

In a device of the character described, a crown cap for a thief hole, as described, having on its periphery a flared shoulder with a plurality of perforations there-through, said shoulder having its under outer portion cut away so as to leave a groove in the upper inner part of said under cut-away portion, said cut-away portion being adapted to receive a rubber gasket; a rubber ring gasket member having a tongue on its 95 upper inner side and an inwardly and downwardly beveled side surface; said groove in said cut-away portion being adapted to receive said tongue of said rubber gasket; a metallic outer ring member being adapted to fit over the outer surface of said flared shoulder and being adapted to be securely fastened thereto, having its inside surface beveled oppositely to said beveled surface of said gasket member, and being adapted to 100 securely hold with holding means said gasket member and crown cap tightly together.
